UNITED STATES PATENT OFFICE.

ALFRED C. STEWART, OF LOS ANGELES, CALIFORNIA.

CARBURETER.

1,228,845.

Specification of Letters Patent. Patented June 5, 1917.

Application filed November 11, 1914. Serial No. 871,616.

To all whom it may concern:

Be it known that I, ALFRED C. STEWART, a citizen of the United States, residing at Los Angeles, in the county of Los Angeles and State of California, have invented a new and useful Carbureter, of which the following is a specification.

This invention relates to a carbureter of the type wherein the liquid fuel is supplied to the carbureting means from a fuel chamber in which a definite level of fuel is maintained by float-operated valve means, and one object of the invention is to provide improved means for temporarily opening such valve to flush the carbureter.

Another object of the invention is to provide for retaining the float controlled valve in closed position, to prevent leakage therethrough, when the carbureter is not in use.

Another object of the invention is to provide improved means for regulating the supply of fuel to the carbureter.

The accompanying drawings illustrate my invention, and referring thereto:

Figure 1 is a side elevation of the carbureter.

Fig. 2 is a vertical section thereof.

Fig. 3 is a section on line x^3-x^3 in Fig. 2.

Fig. 4 is a side elevation of the controlling means for the fuel regulating valve.

The carbureter comprises a casing formed with a fuel chamber 1 and a mixing chamber 2, separated by a partition member 3, which is shown as provided with an annular screw-threaded flange 4 on which the members 1 and 2 are screwed. The fuel chamber 1 is formed as a cup, closed at the bottom. The mixing chamber 2 is shown as provided with a jacket or outer wall 6 having a screw portion screwed on the flange 4. Said mixing chamber is further provided with an inner wall 2' whose lower face engages the partition member 3 to make a tight joint. The space 6' between the outer and inner walls of the mixing chamber serves as a jacket space for receiving hot water or other heating medium, in case a heavy oil is used for fuel; suitable connections 5 and 5' being provided for circulation of such medium through said

space. Mixing chamber 2 is provided with air inlet means 8, consisting for example of a funnel shaped member screwed into the top of chamber 2 and open at its upper end to the outer air, and communicating at its lower end, through an inlet valve opening 8', with the mixing chamber 2. Said mixing

chamber is provided with outlet means 7 having a throttle 7'.

A valve 9 is mounted by its stem 10 to move vertically within the mixing chamber to close or open the air inlet opening 8', said valve-stem sliding in a tubular guide 11 on the partition member 3, and carrying at its lower end a piston 12, working within a cylindrical wall 13 in the fuel chamber 1, forming a dash pot. Valve stem 10 also carries a fuel receiver or spreader 15, having an annular inclined outer wall or lip 15', the valve member 9 extending over said receiver or spreader and sufficiently spaced from said lip to form a narrow annular outlet passage 16 from the space 14 between said valve member and spreader to the mixing chamber. This space 14 in the valve device communicates through openings 18 in the valve 9, with the outer air above the valve; and it also communicates through openings 19, with a passage 20 in the valve stem 10, said passage 20 communicating through openings 21 in the stem and openings 22' in the hub 22 of the dash pot piston, with the interior of the fuel chamber. A spring 24, extending between members 3 and 15, tends to hold valve 9 to closed position.

A float 25 within the fuel chamber 1, is guided by a sleeve 25' thereon, slidable on a portion 26 of the valve stem, said float engaging a lever 27 pivoted at 28 on the casing and having a portion 29 engaging a valve pin 30, which works within a bore 31 in the wall 2' of the mixing chamber and is tapered at its upper end to coöperate with a valve seat 32 formed at the lower end of a tube 33 screwed into an enlarged extension of said bore. The fuel supply pipe is connected to this tube 33, the opening 32' of valve seat 32, being the fuel inlet for the fuel chamber 1. When the device is in non-working position, the float 25 is engaged by the hub 22 of the dash pot piston, the valve-spring 24 at this time holding the valve 9 up within the valve opening 8', and the same spring serving to press the float 25 upward, so as to operate, through the lever 27 to firmly hold the fuel feed valve pin 30 to closed position. Said fuel feed valve pin is formed, by squaring it or otherwise, so as to allow fuel to flow past the body of the pin when the valve is open. Valve stem 10 is provided with a shoulder 36 adapted to engage the sleeve 25' of the float to forcibly depress the float when the air inlet valve 9 is fully opened, thereby provid-

ing for flushing the carbureter, by operation of said air inlet valve.

Means are provided for regulating the flow of oil or fuel in its passage from the fuel tank to the mixing chamber, said means consisting of a taper pin 38 supported within the passage 20 in the valve stem so that it may close or obstruct the passages or openings 19 leading to the receiver or spreader 15. This taper pin is preferably adjustable, being pressed upwardly by a spring 40 and depressed more or less, according to requirements, by helical cam means 41 on a vertically slideable and rotatable pin 42, carrying an operating lever 43, having suitable operating connections, not shown, said cam means 41 engaging a cam means 45 formed as a screw member screwing in a spider 46 on the air inlet member 8. Pin 38 has a shoulder 47, adapted to engage a tubular extension 48 on valve 9, to depress said valve.

The operation is as follows: Normally, or when the device is not in use, the valve 9 is held in raised position, as indicated by dotted lines in Fig. 2, said valve being then within the air inlet opening 8' and cooperating with the seat surrounding said opening to close the same. At the same time the fuel inlet 32' is closed by a valve pin 30 which is held closed by the force of the main valve spring 24 as above stated. When the engine is started and throttle 7' is opened, a condition of suction or partial vacuum is produced in the mixing chamber at each suction stroke of the engine to which the carbureter is connected by its outlet 7, and the valve 9 is thereby drawn down so as to open the air inlet, air then passing from said air inlet, past the edge of the valve 9, to the mixing chamber. The condition of suction in the mixing chamber is communicated through the annular outlet opening 16 to the space 14 within the valve device, with the result that fuel is drawn from the fuel chamber through passages 22', 20 and 19 to the receiver or spreader 15, and also with the result that air is drawn through openings 18 in valve 9 to said space 14 above the receiver or spreader, and this air, passing at high velocity over the fuel in the receiver or spreader, carries the same forward and violently ejects it through the annular outlet in the form of a sheet or spray of mixed fuel and air. This sheet or spray of air and fuel meets the current of air passing the edge of valve 9 at high velocity, from the air inlet to the mixing chamber, and is effectively mixed and vaporized by the action of the impinging air currents. It will be noted that the spring 24 resists the opening of valve 9, under the action of the suction in the mixing chamber, thereby insuring the production of a strong vacuum in the mixing chamber, sufficient to produce the required suction of air and fuel, and as

the valve descends the fuel passages 19 are gradually exposed by movement thereof away from the taper pin 38, so that the fuel is supplied in proportion to the air.

The action of dash pot piston 12 steadies the motion of valve 9 preventing any sudden motion thereof in opening and closing, and in case of sudden opening of the throttle, the retardation of opening of the valve 9, by the action of the dash pot, causes a temporary increase in the suction which increases the fuel supply and gives more rapid acceleration. The action of the spring 24 and the dash pot, in producing an extra high vacuum when the throttle is first opened gives a rich mixture in starting. If, however, it is desired to flush the carbureter to increase still further the richness of the mixture in starting, or at any time when extra acceleration is required, the controlling pin 42 is moved by its lever 43, so as to force the pin down by action of cams 41, 45 and thereby depress the pin 38 until the shoulder 47 thereon engages the top of extension 48 of valve 9 and forces valve stem 10 down, bringing shoulder 36 thereon against float member 25', whereupon the float lever 27 is depressed so that valve 30 opens and allows an extra quantity of fuel to flow to the fuel chamber, thereby flushing said chamber, and producing the required increase of fuel supply, with consequent increase of power. It will be noted that the valve may be opened in this manner irrespective of the level of the fuel in the fuel chamber, and therefore it is possible by this means to raise the fuel above the maximum level required under normal running conditions.

By arranging the float in the fuel chamber around the valve stem and over the piston thereon, and utilizing the said valve stem as a guide for the float, I utilize the space offered by the valve and dash pot construction for the operation of the float, thereby making the device extremely compact. Moreover, the operation of the valve, under normal running conditions, leaves the float free to perform its usual functions, and only limits or controls the motion thereof, at the limits of motion of the valve, as above stated.

What I claim is:

1. In a carbureter, a fuel chamber provided with a fuel inlet valve, a float in said chamber to close said valve when the fuel reaches a definite level in said chamber, a mixing chamber, an air inlet valve therefor, and means connected with said air inlet valve for forcibly opening said fuel inlet valve.
2. In a carbureter, a fuel chamber provided with a float-controlled fuel inlet valve, a mixing chamber, an air inlet valve therefor adapted to open under the suction in

- said mixing chamber, and provided with means tending to move it to closed position, a controlling device for forcibly moving said air inlet valve to open position, and 5 means operated by said air inlet valve for opening said fuel inlet valve.
3. In a carbureter, a fuel chamber provided with an inlet valve, a float in said chamber adapted to close said valve when 10 the float rises, spring operated means supplementing the action of the float, for forcibly holding the inlet valve closed and means operated by suction in the carbureter for acting on said spring operated means to 15 nullify the action thereof on said fuel valve.
4. In a carbureter, a fuel chamber provided with a fuel inlet valve, a float for closing said valve when the fuel in the chamber reaches a definite level, spring operated 20 means for forcibly operating said float to close said valve and manually operated means for acting on said spring operated means to relieve the fuel valve from the action thereof and for acting on said float to
- cause said valve to open irrespective of the 25 level of the fuel in the fuel chamber.
5. In a carbureter, a fuel chamber provided with a float-controlled fuel inlet valve, a mixing chamber provided with a spring-controlled air-inlet valve, and means operated by said air inlet valve to close said fuel inlet valve when the air inlet valve is closed. 30
6. In a carbureter, a fuel chamber provided with a fuel inlet valve and with a float for closing the same, a mixing chamber provided with an air inlet valve, a spring for closing said air inlet valve, and means connected to said air inlet valve to raise the float and hold the fuel inlet valve closed, when the air inlet valve is closed. 35 40

In testimony whereof I have hereunto set my hand, at Los Angeles, California, this 30th day of October, 1914.

ALFRED C. STEWART.
